UNITED STATES PATENT OFFICE.

ELMER F. RIES, OF HARRISON PIKE, CINCINNATI, OHIO, ASSIGNOR TO MAX SCHMIDT, TRUSTEE FOR HIMSELF, ELMER F. RIES, EMIL NEUBACHER, THEODORE O. BUMILLER, AND SIGMUND V. FRIETSCH, ALL OF CINCINNATI, OHIO.

POLISHING MACHINE.

Application filed February 21, 1921. Serial No. 446,585.

To all whom it may concern:

Be it known that I, ELMER F. RIES, a citizen of the United States, residing on the Harrison Pike, city of Cincinnati, county of Hamilton, and State of Ohio, and whose post-office address is box 25, station L, Cincinnati, Ohio, have invented a new and useful Polishing Machine, of which the following is a specification.

10 My invention relates to that class of polishing machines for polishing tubes and rods of circular cross-section, employing abrasive wheels or belts running at a high surface speed. The abrasive agency may either consist of grinding wheels of composite structure such as carborundum, or of natural mineral stones, such as emery or sandstone, or of wheels or belts of fibrous material like felt, leather or layers of heavy 15 duck or muslin and the like, the periphery of which is coated with the abrasive material held in place by an adhesive.

The abrasive agency is hereinafter referred to as an abrasive member and the 20 object worked upon as the rod. I have shown my invention applied in connection with a rotary abrasive wheel. It is obvious, however, that an abrasive belt can be employed without in any way departing from 25 the spirit of my invention.

The object of my invention is to provide 30 means for guiding and automatically feeding past the abrasive member the object to be polished, such as rods and tubes of circular cross-section, by the action of the abrasive member itself. The rods worked upon can be of indefinite length, depending upon 35 the length of the feeding mechanism employed.

40 A further object of my invention is to provide means for adjusting the mechanism of my improved construction to different diameters of rods, to regulate and control the character of finish produced and the 45 amount of material removed by the abrasive member, and to control and regulate the rate of feed of the rods past the abrasive member.

50 My invention consists in the combination and arrangement of the several parts and mechanism with an abrasive member, as herein set forth and claimed, and as illustrated in the drawings, in which:

Fig. 1 is a front elevation of my invention.

Fig. 2 is an elevation of the discharge end 55 of my invention.

Fig. 3 is a plan view, with the cover of the regulating mechanism partly in section for better illustration of the interior parts.

Fig. 4 is an elevation of the infeeding end 60 of my invention with the feeding mechanism in vertical section on a plane corresponding to the line 4—4 of Fig. 3;

Fig. 5 is an elevation of the infeeding end of my invention with the feeding mechanism 65 and the driving means for the finish controlling mechanism in section on a plane corresponding to the line 5—5 of Fig. 3;

Fig. 6 is a vertical section illustrating the 70 finish regulating and controlling mechanism taken on a plane corresponding to the line 6—6 of Fig. 3;

Fig. 7 is a horizontal section of the finish 75 regulating and controlling mechanism taken on a plane corresponding to the line 7—7 of Fig. 5;

Fig. 8 is an inside elevation of the rail 80 showing the mounting of the stationary guide rollers, with the adjustable guide roller brackets removed; and

Fig. 9 is a side elevation of the adjustable 85 guide rollers, housing and bracket therefor.

A preferred embodiment of my invention is set forth in which a usual abrasive member here shown as a wheel 12 is mounted between flanges 14 held in place by clamp nut 15, on shaft 13 running in bearings 16 in frame 17. The shaft has pulley 18 secured thereon and is driven by belt 19 which is here instanced as passing through the 90 hollow of the main frame and driven from below in the usual manner.

When a rod to be polished is held in contact with the surface of the abrasive member, there is a tendency for the same to rotate in a direction opposite to that of the abrasive member. In the mechanism hereinafter described, I take advantage of this fact, in providing a ready path of travel 95 with a minimum of friction and wear, and a maximum of safety. Thus 25 is a feed roller supporting rail, comprising horizontal web 26 and vertical web 27, having thereon main feed rollers 28, the ends 29 of which are journaled in bearings 30, secured to the rail 100 by bolts 31 passing through the horizontal and vertical webs. The rollers 28 are reduced as shown at 32 directly opposite the

105

abrasive member to aid in keeping them clear of deposits of abraded particles of metal and abrasive material, thereby aiding the smooth rotation and passage of the rod.

6 I further provide auxiliary stationary feed rollers 35 journaled on shafts 36, securely held in holes 37 in housings 38. The housings are secured to the rail as by bolts 39 passing through the vertical and horizontal webs. The rollers 35 are of substantially the same diameter and so mounted as to have their axis of rotation substantially in line with the axis of rotation of the main feed rollers 28. Thus should a rod be placed in 10 contact with the main stationary feed rollers 28, it will be in substantial contact with the auxiliary stationary feed rollers 35.

It is found in practice that the rods before polishing are not always of perfect circular form, and often consist of rough black rolled wrought iron and steel bars, or black roll pipe. Accordingly my improved device is used for truing up and removing the scale. To resiliently urge the rod to be polished against the stationary feed rollers, and to permit of the adjustment of different diameters of rod, and yet permit of a free floating contact, I provide adjustable guiding heads 40. There is one of these adjustable 25 guiding heads preferably located opposite each of the auxiliary stationary feed rollers 35, and also one to either side of the abrasive member and opposite to each of the end portion of the main stationary feed rollers 28.

30 The adjustable guiding heads comprise adjustable feed rollers 41, journaled on shafts 42 secured in holes 43 of housings 44 rocking on pins 45 in supporting bracket 46. The brackets are adjustably secured to the rail by bolts 50 passing through slots 51 in the brackets, and threaded into threaded holes 52 in lugs 53 integrally formed on the rail. Washers 54 received under the heads of the bolts aid in firmly clamping the 45 brackets in place. The housings with rollers mounted therein and rocking on pins 45, provide for slight variations in the diameter and inequalities in the rod. Resilient contact between the rollers and rod is had as by 50 means of springs 55 received between the upper ends of the housings and the supporting brackets 46 and about studs 56, having reduced shanks passing through holes 57 in the housing and having their ends riveted over as shown at 58. The studs pass through slots 59 in the brackets and have thumb nuts 60 received over the outer threaded end 61 for limiting the movement of the adjustable feed rollers 41 toward the stationary feed 55 rollers 35 and 28. Adjustable stop screws 62, threaded in threaded holes 63 in the brackets, limit the movement of the housing away from the stationary feed rollers by contacting cross ribs 64 thereof.

66 For adjusting the stationary feed rollers

to different diameters of rods and to regulate the amount of material removed, the feed rail is made to slide to and from the abrasive element, by mounting the same on a laterally swinging bracket 70, having adjusting screw 71 received in threaded bearing 72 therein. A reduced end 73 on the screw is received in hole 74, in the rail. The screw is held against endwise movement as by having a shoulder 75 received against the outer surface of the vertical web of the rail and collar 76 secured to the reduced end as by pin 77, bearing against the inner surface of the web. The hand wheel 78 secured to the outer end of the screw provides means for manually operating the same. The rail is guided in its lateral movement by stud shafts 80 secured in the rail and sliding in bearings 81 in vertical plate 82 of bracket 72. Bolts 84 having washers 85 received under their heads, and passing through slots 86 in horizontal supporting web 87 of the bracket and threaded into threaded holes 88 in the rail securely lock the same in position.

Means are provided for feeding the rods past the abrasive element. When the several parts of my device are so adjusted as to bring the rods into contact with the fast moving abrasive element, a rotary motion is imparted thereto. There is no tendency for the rods to feed to the right or left, if the axis of the abrasive element is in axial alignment with the axis of rotation of the rod. If, however, the rod is brought out of axial alignment, in a vertical plane, the abrasive element will feed the rod in such direction, dependent on whether it is inclined to the right or left. The greater the degree of inclination the greater will be the rate of feed. The bracket 72 for supporting the rail is so mounted as to permit the adjustment of its inclination. I have herein shown the inclination as being towards the right as by mounting the bracket, on a pivot bolt 90 passing through hole 91, in depending plate 92, of the adjustable bracket and threaded into threaded hole 93 of stationary bracket 94 secured to the main frame by bolts 95. The adjustable bracket 72 is clamped in adjusted position by bolt 90 and also by clamp bolt 96 passing through an arc slot 97 and threaded into hole 98 in pendant 99 of stationary bracket 94. Washers 100 under the bolt 90 and washers 101 under bolt 96 aid in firmly clamping the bracket in adjusted position.

When the rods are fed past the abrasive element the rotary motion and feed imparted thereto continually present a new surface to the abrasive element. It is obvious that by governing the speed of the rotary motion of the rod, the character of the surface polished can be controlled. Controlling and regulating mechanism 110 is provided for this purpose. Driving connection 111

is had with the controlling mechanism as by forming pinion 111 on one of the stationary feed rollers, here instanced as one of the rollers 28, and meshing with an idler 112, journalled on shaft 113, secured in bearings 114 of housing 115, said idler 112 meshing with gear 120 secured by pin 121, to shaft 122 journalled in bearing 123, and adjusting nut 124 hereinafter described. Bell cranks 130 having flyballs 131 formed on the outer ends thereof, and received in slots 132 in a flange 133 integrally formed with the gear 120, rock on pins 134. Round contact ends 135 of the bell-cranks engage surface 136 of an endwise slidable friction sleeve 137 which is caused to rotate with shaft 122 as by pin 138 fixed in the shaft having slideable connection in keyway 139 in the sleeve. A friction plate 140 is formed on the sleeve for contacting disk 141 of friction material such as felt received between the said plate and a plane surface 142 located on the housing 115. For normally urging the flyballs to a collapsed relation I provide spring 145 in bore 146 of the friction sleeve. The pressure exerted by the spring against the outward movement of the fly balls is controlled by the adjusting nut 124 as by having a threaded shank 147 formed thereon and received in a threaded bore 148 of the housing.

In practice the stationary feed rollers are adjusted to the proper distance from the abrasive element by manipulating the hand wheel 78 and clamping the rail in place by clamp bolts 84. The adjustable guiding heads are then adjusted and clamped in place by clamp bolts 50 thus bringing the adjustable feed rollers in contact with the circular rod for holding it against the stationary feed rollers. To compensate for such inequalities of the rod as there may be, the stop screws 62, are placed in the proper position, the thumb nuts 60 having been previously adjusted to regulate the tension on rollers 41 by spring 55.

The rail is now adjusted to the proper inclination consistent with the rate of feed desired, and clamped in adjusted position by pivot bolt 90 and clamp bolt 96. The adjusting nut 124 is now adjusted to give the proper tension on spring 145, to regulate the speed of rotation of the rod, while worked upon, through the medium of controlling mechanism connected with the stationary feed rollers.

In practice it is usual to feed the rods from the left to the right (see Fig. 3 arrow 60 "a"). The operator stands at the left end of the rail feeding the rods into the space 150, formed between rollers 41, 28 and 35. The rods are pushed forward into contact with the abrasive element moving with high speed in the direction of the arrow "b", (see

Figs. 4 and 5), which imparts rotary motion thereto, by the pressure of the abrasive on its outer surface. The surface speed of the abrasive element is substantially greater than that of the rod, as a considerable retarding effect is had by the inertia of the abrasive element and further the frictional resistance exerted by the feed rollers. The controlling mechanism acts to control the speed of the rod and thereby the finish. The slower the speed of the rod the higher the finish. Due to inequalities, the speed of the rod is sometimes retarded or increased. The finish produced is therefore not uniform. The controlling mechanism regulates the speed of rotation by the centripetal action of the flyballs 131 driven through the train of gears 111, 112 and 120, when the speed increases beyond a desired point. The flyballs act to add a frictional resistance through the medium of bell cranks 30, and endwise slidable sleeve 137, the friction plate 140 thereon, contacting friction disk 141 which in turn contacts plane surface 142, on housing 115, thus retarding the speed of the feed rollers and the rod. The greater the speed the greater the pressure exerted by the flyballs against the friction plates. The momentary increases and decreases in the speed of rotation of the rod are thus effectively guarded against.

The rail being inclined downwardly to the right and out of axial alignment with the axis of rotation of the abrasive element, the rod is fed along automatically, every portion of its surface being successively presented to be worked upon. The momentum of the rod is sufficient to carry it beyond the rollers after the abrasive element is passed.

It will be noted that it is unnecessary to employ skilled workmen. The position of the operator is such as to provide a maximum of safety, he being stationed at a considerable distance from the abrasive element and further his hands do not touch the rods while they are being worked upon.

What I claim as new and desire to secure by Letters Patent is:

1. In a polishing machine, a main frame, an abrasive element, operatively mounted in said frame, an inclinable work support adjustably secured to said frame, comprising a rail, a plurality of guide rollers mounted on said rail, a plurality of guiding heads adjustably mounted on said rail, coacting with said guide rollers, means for adjusting said work support toward and from said abrasive element, and means for inclining said work support.

2. In a polishing machine, a main frame, an abrasive element operative in said frame, a work support, rollers on said work support for carrying the work so arranged as

- to be capable of having motion imparted thereto by the action of said abrasive element on said work means for adjusting said work support toward and from the said 5 abrasive element, means for adjusting the inclination of said work support for controlling the rate of feed of the work, means for clamping said work support in adjusted 10 position, a regulating and controlling instrumentality mounted on said work support, and a driving connection between said rollers and said regulating and controlling instrumentality for regulating the speed of rotation of the work carried on said rollers.
- 15 3. In a polishing machine, a work support, comprising a supporting rail, a plurality of main feed rollers, bearings for said feed rollers, secured to said rail, a plurality of auxiliary feed rollers, bearings for said 20 auxiliary feed rollers secured to said rail, and said main feed rollers and auxiliary feed rollers so arranged as to have their work contacting surfaces in alignment with one another.
- 25 4. In a polishing machine, a work support, comprising a supporting rail, a plurality of main stationary feed rollers, bearings for said feed rollers and secured to said rail, a plurality of auxiliary stationary 30 feed rollers, bearings for said auxiliary feed rollers mounted on said rail, said main feed rollers and auxiliary feed rollers so arranged as to be in axial alignment with one another, a plurality of adjustable guid-
- ing heads, comprising adjustable feed rollers, shafts on which said adjustable feed rollers are journalled, rockable housings in which said shafts are secured, pins on which said housings are adapted to rock toward and from the stationary feed rollers, brackets to which said housings are rockably secured, said brackets adjustably secured to said supporting rail, a spring member between the said housings, and said brackets, 40 adjusting means for adjusting the said housings toward and from the stationary feed rollers, and a limiting means for limiting the movement of said housing toward the said brackets.
- 45 5. In a polishing machine, a guiding head comprising a plurality of feed rollers, shafts on which said feed rollers are journalled, a rockable housing in which said shafts are secured, a pin on which said housing has rocking movement, a bracket in which said pin is secured and having a slot therein, a stud in said rockable housing, adapted to project through said slot, a spring secured about said stud and between 50 said bracket and said housing, a threaded portion formed on the outer end of said stud, a thumb nut received over said threaded portion for adjusting said rockable housing toward and from said bracket, and an adjusting screw in said bracket adapted to 55 limit the movement of said housing toward said bracket.

ELMER F. RIES.
